UNITED STATES PATENT OFFICE.

IRA IRL TUBBS, OF SUPERIOR, WISCONSIN, ASSIGNOR OF ONE-HALF TO GEORGE F. MILLER, OF MENOMONIE, WISCONSIN.

INFLATED BALL.

Original application filed September 22, 1924, Serial No. 739,127. Divided and this application filed December 10, 1927. Serial No. 239,152.

This invention relates to an improved inflated ball of the type used for playing basket ball. It is to be understood, however, that the construction can be used in connection with any ball which is provided with a cover of leather or other flexible material and inflated through the medium of a bladder positioned in the cover and inflated when it is desired to use the ball. Balls of this character are also used for playing football, water polo and many other games and are also used as punching bags.

One object of the invention is to provide an improved method of closing the cover of a ball containing an inflated bladder. The usual construction is to provide a lace, a part of which at least is on the outside of the cover and which is pulled tight by hand. This invention would eliminate any work in connection with the fastening of the cover around the bladder, and the only act necessary to close the outside container firmly and tightly around the bladder would be by the inflation of the bladder itself.

Another object of the invention is to so construct this cover that the portions thereof upon opposite sides of the opening will be drawn toward each other to close the opening as the bladder is inflated, the bladder when inflated engaging the closing means to impart movement to the same to effect the closing of the opening.

Another object of the invention is to so construct this cover that the opening will be closed simply by the inflation of the bladder, thus making it a very simple matter to prepare the ball for use and further permitting the ball to be blown up under a high pressure. It should be noted in this connection that the higher the air pressure, the tighter the cover will be drawn upon to close the opening.

Another object of the invention is to provide improved means for mounting the bladder within the cover with the air inlet of the bladder communicating with an opening in the cover so that the bladder can be expanded and air let out or more air applied or in other words forced into the bladder from the outside of the ball without it being nec-

essary to interfere in any way with the opening through which the bladder is inserted into the cover.

Another object of the invention is to make it possible to construct an outer covering for the ball which will be free from perforations, lacings, or outward projections of any character whatsoever, and to afford a perfectly regular, smooth surface.

Another object of this invention is to provide a ball which will be regular in form and elasticity so that pressure applied to any part will produce exactly the same reaction.

The present case is a division of application Ser. No. 739,127, filed September 22, 1924, and some of the matter disclosed herein is claimed in the parent case.

The invention is illustrated in the accompanying drawings, wherein:

Figure 1 is a view showing the improved ball in top plan and looking at the side having the inlet opening formed therein.

Figure 2 is a sectional view taken along the line 2—2 of Fig. 1.

Figure 3 is a view similar to Fig. 1 showing the ball with the air let out of the bladder and the inlet opening spread for insertion or removal of a bladder.

Figure 4 is a transverse sectional view taken along the line 4—4 of Fig. 3.

Figure 5 is a fragmentary sectional view taken along the line 5—5 of Fig. 1 with the bladder in place but not inflated.

The fundamental purpose of this invention is to cause the opening in the outside container to close upon the inflation of the bladder. The exact method for individual types of balls may vary slightly.

The object is accomplished in this invention either by the use of one single lace, or by the use of several laces or strips, as occasion may require. A single lace may be woven back and forth through loops, holes, hooks or devices of a similar character in the flaps along or near the opposite edges of the opening and other flaps spaced outwardly from the first named flaps. When individual strips are used, they may extend from the last named flaps to or near the opposite edges of the opening. The lacings are to be used

when it is desired to constantly equalize the tension. This equalization may be secured by the use of one or more lacings.

This improved playing ball is provided with a cover 1 formed of leather or any other suitable material and if desired formed in a number of sections stitched together after the manner usually employed in constructing basket balls, punching bags, foot balls or other balls of similar construction. This cover is provided with an opening 2 in the form of an elongated slit which when in the closed position will appear as shown in Fig. 1, but which may be spread to an open position as shown in Fig. 3. A small opening 3 is formed in the cover to one side of the slit or main opening 2 and registers with the internally threaded neck 4 of the socket plate 5 secured to the inner face of the cover. This plate 5 is provided with a covering 6 formed of any suitable material such as thin leather or a suitable fabric, the covering 6 serving to prevent chafing of a bladder placed within the cover. A cushion 5' preferably of rubber, may be inserted between the socket plate and the cover. The purpose of this cushion is to absorb the jar when the part of the cover directly at the outside of the socket plate comes in contact with the floor or other surface. Were the leather cover of the ball directly in contact with the socket plate there would be more of a shock and a greater sound and the ball would not bounce as well. This bladder 7 is inserted into the cover through the opening 2 and is provided with a threaded valve neck 8 which may be screwed up into the neck 4 as shown in Fig. 5. The detail construction of the valve-control neck is not shown since this will be similar to the construction of a valve-control inlet used in connection with an inner tube of a tire.

Flaps 9 have been shown secured to the inner side of the cover 1 at opposite edges of the opening 2 and other flaps 9' are secured to said inner side of the cover in outwardly spaced relation with said flaps 9, all of the flaps extending toward the opening 2. Any or all of these flaps may be formed by folding a strip of leather or the like upon itself and stitching its edges to the cover 1, the flaps 9 being shown of this form while the flaps 9' are illustrated merely in the form of strips stitched at one edge to the cover. Strips or lacings 10 extend across the opening 2 and are connected to the flaps 9 and 9'. These strips or lacings are of such length that when the bladder is inflated, the portions of the cover upon opposite sides of the opening will be drawn toward each other and into edge contact as shown in Figs. 1 and 2 to entirely close the opening 2 with the flaps and strips positioned in close contact with the inner face of the cover. In the construction shown, the flaps 9 and 9'

are formed with spaced eyelets and there are two lacings 10 interlaced with these eyelets, each lacing connecting the flap 9 at one edge of the opening 2, with the flap 9' at the other edge of said opening.

70

When the ball is to be inflated, the threaded valve neck 8 may be first screwed into the threaded neck of the plate 5 and the bladder thereafter inserted into the interior, or vice versa. The threaded valve neck 8 will be screwed into the threaded neck of the plate 5 so that a suitable pump such as a bicycle pump can be employed to inflate the bladder. When the bladder is inflated it is expanded and as it expands it will distend the cover and through engagement with the flaps 9', cause the strips or lacings 10 to be drawn upon, which in turn will draw upon the flaps 9 and draw the cover to entirely close the opening 2. It will thus be seen that the greater the air pressure, the greater will be the pull applied to the strips or lacings 10 and the tighter the opening will be held in a closed position. It will further be noted that the protecting strip 6 will prevent chafing which might tend to wear the bladder and also that the air can be readily let out or the pressure increased without it being necessary to open the cover. It will be further noted that the inlet of the bladder is not liable to be damaged as in the case where a bladder is provided with a neck of rubber tubing which must be folded over and secured by a rubber band, piece of string or other fastener.

It is claimed and desired to secure by Letters Patent:

1. In an inflatable ball of the class described, a bladder and a cover, a valve stem for said bladder, an elongated slit in said cover for the insertion of said bladder, means spaced from said slit for supporting said valve stem and for providing access thereto from the exterior of the cover when said slit is closed, reinforcing strips associated with said slit, each of said reinforcing strips being folded upon itself and being secured to one of the margins of the insertion opening with its folded edge presented to the slit, said reinforcing strips affording pockets through which a lace may be extended in lines parallel to the slit, a plurality of pairs of oppositely located apertures formed in the folded edges of said reinforcing strips, and a lace passing across said slit on the inside of the cover and being passed parallel to the slit through said pockets, substantially as described and illustrated.

2. In an inflatable ball of the class described, a bladder and a cover having an elongated slit therein for the insertion of the bladder, invisible means for closing said slit comprising elements associated with the inner surface of the cover and located adjacent said slit affording elongated pockets

- through which a lace may be passed in parallelism with the slit, a plurality of spaced pairs of oppositely disposed apertures affording means of ingress and egress for said 5 pockets, and a lace passing in and out of said apertures extending across said slit on the inside of the cover and through said pockets in parallelism with the slit, substantially as illustrated and described.
- 10 3. A pneumatic ball comprising a flexible cover having an opening formed therein, an inflatable bladder in said cover, and bladder actuated means for moving portions of said cover upon opposite sides of said opening toward each other to close said opening when said bladder is inflated, said bladder actuated means comprising flaps secured to the inner face of said cover upon opposite sides of said opening and remote therefrom, 15 other flaps similarly secured adjacent said opening, and lacing extending in crossed relation across said opening and slidably connecting said remote flaps with said flaps adjacent said opening.
- 20 4. A pneumatic ball comprising a flexible cover having an opening formed therein, an inflatable bladder in said cover, and bladder actuated means secured to the inner face of said cover for moving portions of said cover upon opposite sides of said opening toward each other to close said opening when said bladder is inflated, said bladder actuated means comprising flaps upon opposite sides of said opening adjacent thereto and terminating short of said opening, and automatically adjustable means connected with said flaps to draw upon said cover and close said opening when said bladder is inflated.
